TWO-WAY DOUBLE STEPLADDER

Emanuel R. Morando, New York, N. Y.

Application March 18, 1942, Serial No. 435,153

2 Claims. (Cl. 228—28)

This invention relates to a double step-ladder, and has particular reference to a work ladder for two persons.

The main object of this invention, is the back to back arrangement of two step-ladders, one at each end of the service head table, each of which may be moved in towards each other when not in use.

One of the objects of this invention, is the provision of an organization in which the constituent elements are so arranged structurally and functionally as to assure improved and beneficial results with inexpensive structure which is easy to manufacture and which may retain its efficient working qualities, without renewal of parts, for a relatively long period of time. A feature of the disclosure resides in the combination of a pair of step-ladders which are surmounted by one head table.

Another object of this invention, the adaptation of the two ladders to swivel on each end of the service head table, in which they may be swiveled from their end position as a double step ladder, to the front position whereof the top service table may bear against the wall, or be supported by a brace.

As herein disclosed the device is illustrated as a short ladder, of the type of a so-called set of steps, but the disclosure is not so limited, since the principle and substantial structure thereof may be incorporated in a longer ladder, or in a device of this kind which may have the legs thereof joined, or of the type well known as extension ladders.

Another object of this invention is the provision of a ladder in which the leg and step structures may be instrumental in serving as means for carrying other conveniences, such as a flexible container or receptacle means for holding tools and the like, and to provide a ladder in which, having a relatively large service head table therein, is of such formation that a user may transfer from one part thereof, on the same level, to another part, so that all parts of said table may be reached without difficulty. The double drawer arrangement under the service head table provides for an assortment of braids, nails, screws, and other necessary supplies needed, in which two workers may operate at the same time, on the same plane or level, so that both may cooperate, or assist or help the other. The instant ladder may be used on all places, such as the household, factories, business places or stores, where ladders of the single ladder type have heretofore been used.

With the above indicated objects, features and advantages in view, as well as others, which will hereinafter appear, this invention resides in the structures, combination and arrangement of parts hereinafter fully described and illustrated in the accompanying drawing, in which:

Figure 1 is a front elevational view of the improved double step-ladder of this invention;

Figure 2 is an end view thereof;

Figure 3 is a top plan view of the flexible tool holder;

Figure 4 is an end view, similar to Fig. 2, except in this instance the double ladders have a swivel connection to the service head table;

Figure 5 is a front view of Fig. 4;

Figure 6 is a modification of the ladder steps.

Referring to the drawing, each ladder includes a pair of legs 10, 11, between which are steps 12 secured to the legs 10 and 11, by any suitable means, such as by the brackets 13 and bolts 14, to make same firm and durable. The steps 12 are of such distance apart, on the respective leg members, as to be conveniently accessible to the feet of a user while mounting the device. These steps 12 may be slightly elevated at the rear side thereof as noted in Fig. 1, or may be elevated at the front, if so desired.

Each ladder 15 and 16 is connected by metal brace members 17, the ends of which are suitably connected to the steps or legs. The braces 17 may have a medial joint or hinge 18 therewith and the end attaching means therefor may be bolts, such as the element 19.

A work table, to be known as a service head table 20 mounted on the tops of said legs includes a rectangular slab of wood or any other suitable material, this slab or member being of such longitudinal and transverse extent as to project beyond the ends of the legs 10, 11.

At the top ends of the legs 10 and 11, a plate 22 and bracket 23 form a pivotal connection 24 to the underside of the service head table 20. At opposite ends of drawers 27 are a pair of wood brackets or cleats 25, each of which rest onto the inwardly projecting ribs 25. The ribs 25 form a track for a double drawer assembly that provides a seat for sliding the drawers 27, which have divided compartments 28 therein to deposit nails, screws, or any supplies needed for the work to be done.

In Figures 4 and 5, the double ladders are shown in an alternative form, whereby in the table top 20 a swivel or turntable connection 35 is placed on a fixed plate 42 having a bearing 42'. This swivel connection provides

means to arrange each ladder 15' and 16' to be set either in the end and self standing positions as shown in dot and dash lines or in a right angle and front position, as shown in full lines, or in any universal position of a complete circle. This allows the table 20' to bear against a wall as at 36. However, if so desired, a brace member 37 shown in dot and dash lines may provide convenient supports to each ladder in which event, the service table 20' does not bear against the wall. When not in use, this brace may be moved in parallel relation to the outer legs 10, and secured thereat by a thumb screw 38 into a slot 39 of the brace. A locking bar 40 with holes 41 therein provide means to position the brace 37 as desired. Similar parts with their numerals are primed over the same numeral shown in Figures 1 and 2. Brackets 23' on legs 10 and 11, are secured to the cross-plate 42.

On each end of the table 20 are two reversible hooks 45, that may be swung over a pinhook 46 in an optional position as shown in Fig. 2, and on the hooks 45 may be removably suspended a paint pail, tool bag or container 48.

In Fig. 3 a tool receptacle includes a lowermost sheet metal or flexible strap member 50 and an upper narrow strap 51. The strap may have angularly turned, integral attaching flanges 52, conventionally represented in the drawing, thereby providing pockets 54 a certain space therebetween, as seen in Fig. 1. Fastening means, such as by stitching at 55, may be used for securing said flanges, and between the top and bottom straps are similar divisional segments, which are formed into loops or pockets or impletions 54, as shown, of different sizes, for tools, brushes or the like.

The disclosure includes further under, or sub-tables, also each alike and one on each pair of legs or set of ladder steps. An under-table, having a leaf 56 is swingable between an upward or folded position, or extended to a working position, the latter being shown in a dot and dash lines in Fig. 1 in association with a top step 12.

The leaf 56 in the present instance has a recessed portion 57, has attached thereto as by fastening elements, a pair of lugs 58, one at each side. The lugs are apertured and have therein a pin 59, the latter being fast with the ladder legs thereat, onto which the pins 59 of the table leaf is pivoted. Stop pins 60, one for each under table, find terminal fastenings in the legs 10, 11,

and on these pins the tables rest, as shown in full lines, when not required for use.

Variations may be resorted to within the scope of the invention and claims, and parts of the improvements may be used without others. Similar parts of the convertible form shown in Figs. 4 and 5, are designated by the same numeral, or are primed therewith.

Having thus described my invention what I claim as new and desire to secure by Letters Patents of the United States of America, is as follows:

1. In a two-way double step ladder of the character described, a pair of individual ladders, each of which is pivotally connected at the top portion thereof, to the underside of a rectangular service head or work table, said ladders being provided with medial braces connected therewith, said ladders adapted to be swiveled from their self standing end position to a right angle front position or to the rear of said work table, whereby it may bear against any object, said ladders provided with vertical braces that may be optionally used in said front or rear positions, said work table provided with pull drawers in between the top portions of said ladders, reversible hooks arranged onto the end portions of said work table, either for the front or rear positions of the ladders, each of 30 said ladders provided with an under-table adaptable to be swung from its normal resting vertical-like position onto the upper step portion of said ladders, to a working horizontal position, a tool receptacle flexibly connected to the side legs 35 of said ladders adjacent the under-table, said tool receptacle having spaced pockets for holding tools, said ladders adapted to be turned in towards each other at their upper pivotal connection to said work table, when not in use, 40 whereat said tool receptacles, and medial braces connecting said ladders are collapsible and foldable accordingly.

2. In a universal two-way double step ladder of the character described, including separate step ladders swivelly connected to a top service or work table, said swivel connection providing a turntable thereat for each separate ladder, so either may be turned to any desired position to said service or work table, each of said ladders having their side leg members also pivoted to a plate member forming part of the swivel connections, whereby said ladders may be swung inwardly or outwardly as may be desired.

EMANUEL R. MORANDO.
